UNITED STATES PATENT OFFICE

112,109

DESIGN FOR A TEXTILE FABRIC

Curt E. Forstmann, Montclair, N. J.

Application February 16, 1938, Serial No. 75,191

Term of patent 14 years

To all whom it may concern:

Be it known that I, Curt E. Forstmann, a citizen of the United States, residing at Montclair, in the county of Essex and State of New Jersey, have invented a new, original, and ornamental Design for Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design comprises a series of spaced stripes extending in a weftwise direction, each composed of spaced groups, each group consisting of three parallel stitches, the groups of stitches in adjacent stripes being staggered whereby said groups arrange themselves also into diagonal stripes.

I claim:

The ornamental design for a textile fabric, as shown and described.

CURT E. FORSTMANN.
